LOUD SPEAKER BAFFLE

Josef J. Hammes, St. Louis, Mo., and Dominick F. Loscalzo, Long Island City, N.Y., assignor to Lowell Manufacturing Company, Maplewood, Mo., a corporation of Missouri

Filed Sept. 18, 1961, Ser. No. 66,731

Term of patent 14 years

(Cl. D26—14)

Fig.5

FIGURE 1 is a top plan view of the loud speaker baffle showing our new design;

FIGURE 2 is a view in front elevation of the baffle;

FIGURE 3 is a view in side elevation of the baffle taken from the right hand side of FIGURE 2;

FIGURE 4 is a sectional view taken along the line 4—4 of FIGURE 2 looking in the direction of the arrows; and FIGURE 5 is an enlarged perspective view of the front of the baffle.

We claim:

The ornamental design for a loud speaker baffle, as shown.
